UNITED STATES PATENT OFFICE

163,507

RADIO CABINET

Samuel E. Adler, Chicago, Ill., assignor to Admiral Corporation, Chicago, Ill., a corporation of Delaware

Application March 30, 1951, Serial No. 14,675

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Radio Cabinet, of which the following is a specification, reference being had to the accompanying drawings, forming part thereof.

Fig. 1 is a front and elevational view of a radio cabinet, showing my new design;

Fig. 2 is a top plan view of the same;

Fig. 3 is an elevational view of the right side of the cabinet;

Fig. 4 is a sectional view the planar origin of which is indicated by line 4—4 of Fig. 1; and

Fig. 5 is a fragmentary sectional view the planar origin of which is indicated by line 5—5 of Fig. 1.

The left side of the cabinet resembles the right side and the back is plain.

I claim:

The ornamental design for a radio cabinet, as shown and described.

SAMUEL E. ADLER.
